UNITED STATES PATENT OFFICE.

WILLIAM M. LORENZ, OF NEW YORK, N. Y.

INTERNAL-COMBUSTION ENGINE.

Specification of Letters Patent. Patented Mar. 21, 1916.

1,176,383.

Application filed March 3, 1915. Serial No. 11,675.

To all whom it may concern:

Be it known that I, WILLIAM M. LORENZ, a citizen of the United States, and a resident of the borough of Brooklyn, of the city of New York, in the State of New York, have invented certain new and useful Improvements in Internal-Combustion Engines, of which the following is a specification, reference being had to the accompanying drawings, forming a part hereof.

10 This invention relates to internal combustion engines of the four-cycle type and is concerned particularly with the improvement of the valve gear therefor whereby it becomes possible to operate such engines at maximum efficiency.

15 The general objects of the invention are to provide a motor which shall not only be highly efficient, as the term is generally used, but shall embody the characteristics of economy, power, compactness, lightness, flexibility, simplicity, reliability and cheapness of manufacture. In motor design, certain underlying principles are recognized 20 and these principles are always sought to be embodied to a greater or less degree by engineers. For instance, it is known that a combustion chamber of maximum volume and minimum radiating surface will give 25 the most efficient transformation of heat units into mechanical power. Further, it is known that ports of maximum area for the intake of the fresh gas and the exhaust of the products of combustion, should be employed and that the controlling valves for 30 these ports should operate quickly so as to close and open the ports in the shortest possible time. The importance of these principles and others which are equally well 35 known to engineers have resulted in the general use of puppet valves for the control of the ports of internal combustion engines and have precluded, for these reasons and others which will appear hereinafter, the general 40 use of sliding valves of any type. It is true that attempts have been made to realize all of the advantages of sliding valves and eliminate the disadvantages of puppet valves, by embodying directly in the motor 45 construction, sliding sleeves in which the power pistons reciprocate, which sleeves are 50 adapted to control the ports, or by building directly in the cylinder head rotary sleeves for the control of the gases. These makeshifts, however, have not proven to be satis-

factory commercially and so it is sought by the present invention to satisfy all of the requirements of good motor practice and provide an engine in which the ports shall be controlled by a sliding valve of such character as to eliminate all of the objections to puppet valves and embody all of the stated objects particularly enumerated above.

Reference is now to be had to the accompanying drawings for a detailed description of the invention, in which—

Figure 1 is a fragmentary view in vertical section, taken on the planes indicated by the broken lines 1—1 of Fig. 6 and looking in the direction of the arrows, and showing an engine constructed in accordance with the present invention and equipped with the improved dual piston valves. Fig. 2 is a view in vertical section, taken on the planes indicated by the broken lines 2—2 of Fig. 6 and looking in the direction of the arrows and showing particularly the relationship of the two proximate cylinders of an engine, the dual valves for controlling the same, and the actuating shaft for said valves. Fig. 3 is a view similar to Fig. 1 showing in vertical section, along the line 3—3 of Fig. 5 and looking in the direction of the arrows, an engine provided with an improved valve of the simple piston type. Fig. 4 is a view in section similar generally to Fig. 2, but showing the modified form of valve, and taken on the planes indicated by the broken lines 4—4 of Fig. 5, two proximate cylinders of the engine in this embodiment having their intake ports controlled by a single common valve and their exhaust ports controlled by a separate but single common valve. Fig. 5 is a view in horizontal section through the engine shown in Figs. 3 and 4. Fig. 6 is a horizontal section through the engine shown in Figs. 1 and 2.

As this description proceeds, it will appear that the present improvements may be applied to two cylinders or any multiple thereof, but for the purpose of this description it has been elected to show two of the cylinders of a four cylinder motor. The valve mechanism and other details of construction will be duplicated for the other two cylinders of such a four cylinder motor and so it is unnecessary to make specific reference to these additional cylinders except in so far as it becomes important to main-

105

110

tain the proper phase relation between the cycles of the pistons of these additional cylinders and the piston of the cylinders to which the description will apply. As shown in Fig. 6 the two cylinders *a*, *b* can be cast integral and have formed directly therein a common port *c* through which it may be supposed that the fresh gas passes into each of the cylinders. A corresponding common port *d* through which the products of combustion from each of the cylinders may pass, will also be provided in the cylinder walls. In the interest of compactness and cheapness of manufacture, the cylinders *a*, *b* communicate with the common ports *c*, *d*, through the converging cylinder ports *a'*, *b'*, respectively, and these last named ports open into chambers *a*², *b*², respectively, for the reciprocating dual piston valves, indicated generally at *c*, *f*, hereinafter to be described. The cylinders *a*², *b*², for the improved valves are also in communication with the common port *c*. The common exhaust port *d* also communicates with the two cylinders *a*, *b*, through cylinder ports corresponding to the ports *a'*, *b'*, one such exhaust port being indicated in Fig. 1 at *b*². By this construction, it will be evident that each of the improved valves *c*, *f* is so disposed as to control the inflow of fresh gases and the outflow of the burnt gases from one of the cylinders *a*, *b*, the valve *c*, in the illustrated embodiment, serving to control the cylinder *b* and the valve *f* serving to control the cylinder *a*. It will be understood that by reason of the integral character of the two cylinders *a*, *b*, and the cylinders *a*², *b*², for the valves *c*, *f*, and the provision of a common inlet port *c* and a common discharge port *d*, great compactness is secured, the initial cost is greatly reduced and provision for cooling the cylinders *a*, *b*, as by means of the water jackets *a*³, *b*³, can be embodied in the structure very readily and in such relation to the parts of the motor as to insure efficient cooling thereof.

The general structure of the improved motor and the relationship of parts having been pointed out, so far as the embodiment in Figs. 1 and 2, is concerned, it now remains to describe in some detail the form of the valve shown in these figures. Inasmuch as the valves *c*, *f*, are identical, it will be sufficient to describe only one of them, for instance, the valve *c*. This valve comprises a tubular piston *c'* on the circumference of which are formed ports *c*² and *c*³ adapted to register with the inlet ports *c* and the cylinder port *b*², to permit the passage of gases into the cylinder, and this piston *c'* is also provided with other ports *c*⁴ and *c*⁵ adapted to register respectively with the cylinder port *b*² and the exhaust port *d*, to permit the escape of burnt gases from

the cylinder *b*. This tubular piston *c'* is connected to the outer piston *c*, which is hinged on eccentric strap *n*, which is mounted with an eccentric *g* formed on the actuating shaft *i* which is journaled in the motor base and is driven from the crank shaft *k* in any convenient manner, the same not being illustrated. Within the tubular piston *c'* is slidably disposed a solid piston *c*, through which are cut channels *c*⁶ and *c*⁷, which are adapted to be brought respectively into alignment with the exhaust ports *b*², *d*, and the inlet ports *a*², *b*². These channels *c*⁶, *c*⁷, of course, register, respectively, with the ports *c*¹, *c*², and *c*³, *c*⁴, in the piston *c*, as far piston *c*, when the inflow of cylinder *b*, gases is to be permitted. The inner piston *c* carries a connecting rod *c*⁸ which connects through the connecting rod *c*⁹ for the reciprocating piston *c* and have pivotally connected thereto at its lower end, an eccentric strap *m* which engages an eccentric *m* also carried on the actuating shaft *i*. The pivotal connection *m* between the connecting rod *c*⁹ and the eccentric strap *m* can be arranged to rotate so as to rotate in a slot *c*¹⁰ formed in the connecting rod *c*⁹ for the outer piston *c*. It is to be noted that the valves just described and the connections between the pistons and the actuating shaft *i* are all completely disposed so as to be cast integral with the cylinders *a*, *b*. The cylinders *a*², *b*² for the valves *c*, *f* may be closed at their upper ends by threaded caps *a*⁵, *b*⁵ which can be removed readily for the purpose of inspecting the valves *c*, *f*, or for removing the same from their cylinders. This ready accessibility is one of the features of the improved valve construction.

In operation, the shaft *i*, which may be geared to the crank shaft *k* in such manner as to rotate at half the speed thereof, as is usual, drives the eccentrics *g*, *m*, and through the eccentrics, the sliding pistons *c'*, *f*, respectively. The relationship of the eccentrics *g*, *m* is such that the two telescoping pistons *c'*, *f*, are moved in definite phase relation to the crank shaft *k* and register at proper times to permit the inflow of gases into the cylinder *b*, the compression and ignition thereof, and the exhaust of the burnt gases from the cylinder after the working stroke. The other valve *f* which controls the proximate cylinder *a* has its connecting rod *f*¹ and *f*² respectively, carried on the eccentric *m* and connected through suitable means to the pistons, as in the manner described with respect to the dual valve *c*. It will be understood that the eccentrics *g*, *m* have a definite relation to the eccentric *g* and *g*, as will all other eccentrics *g* and *g* on the shaft *i* intended for the control of valves formed in additional cylinders *a*, *b*, in the case of a four cylinder motor. The shaft *i*

portance of maintaining the controlling valves of any motor, no matter what the number of cylinders, in certain definite relation to each other and to the cycle of operations in the various cylinders, need not be emphasized as this is elemental in motor practice.

In the other form of controlling valve, it will be noted from Fig. 5 that the cylinders A, B, are cast integral as before, but instead of having a single valve to control the inflow and exhaust of gases for each cylinder, a single valve, such as E, is employed to control the inflow of gas to both cylinders and a separate valve F is employed to control the exhaust of gases from both cylinders. In this construction, it is preferable to provide a common inlet C for the two cylinders A, B, on one side of the cylinders and to form the common exhaust port D at the other side of the cylinders. Inlet ports A', B', are formed in the walls of the cylinders A, B, and converge to communicate with the common inlet port C, and outlet ports A³, B³ are formed at other points in the cylinder walls and converge to communicate with the common discharge port D. The improved sliding piston valve E is disposed within a valve chamber A² formed in the walls of the cylinders A, B, and serves to control the flow of gas from the common port C into the cylinders, while the other improved sliding piston valve F is disposed in its valve chamber B² and serves to control the outflow of burnt gases from the cylinders to the common exhaust port B. The pistons E and F are identical in construction and so a description of one of the pistons, E, will suffice. This piston E is of the usual trunk form and has therethrough horizontally inclined channels E', E² disposed at different levels and serving, respectively, to place the common inlet port C in communication with the cylinder B and the cylinder A. It will be evident that these channels E', E² must diverge generally to an extent dependent upon the divergence of the ports A', B' in the cylinder walls. Further, it will be understood that the inlet ports A', B' are at different levels in the walls of the cylinders so as to be placed in communication successively with the inlet port C when the piston E is reciprocated. The reciprocation of the piston valve E in its cylinder A² may be effected conveniently by means of a connecting rod E³ and crank E⁴ secured to a small crank shaft I which may be geared in a two-to-one ratio with the crank shaft K. The cylinder A² may, as in the other embodiment of the invention, be cast integral with the cylinders A, B, so that all the valve parts are completely incased, and the upper end of the valve cylinder A² may be conveniently closed by a threaded cap A⁵ which may be removed for the purposes of inspection, re-

pair or withdrawal of the piston valve E. In order to bring about proper control of the ports A', B', it will usually be found necessary to place a rib C' transversely across the inlet port C, so that the channels E', E² will be blanked during certain positions of the valve E. Again to bring about the required compensation for the changing increments of lineal travel of the valve E at different positions of the crank E⁴, it will probably be desirable to form the channels E', E² of greater height than the height of the co-operating ports A', B'. This additional width of the channels is such that the ports A', B' will be kept open, when required, for a greater time than would be the case if the channels and ports were of the same cross sectional area.

Structurally, the valve F is identical with the valve E, but, being disposed at the opposite side of the cylinders A, B, it is necessary to provide a separate actuating small crank shaft F' for this valve, this small crank shaft, of course, being geared also to the main crank shaft A and bearing a definite phase relation to the small crank shaft I, whereby the operations of the exhaust and intake valves are timed properly with respect to the cycles of operation of the various cylinders, no matter what the number of cylinders. As shown in Fig. 4, where it is assumed that the two cylinders are part of a four cylinder motor, the proximate cylinders must have the connecting rods q of the working pistons r connected to the crank shaft K, in the same plane. The connecting rods for the other two cylinders (not illustrated) will also be secured to the crank shaft K in the same plane with each other, but at 180° to the points of connection of the connecting rods q. In this construction the cylinders of the motor will not fire in the usual order, as, 1, 2, 3, 4, but will fire in an order which might be expressed as 1, 3, 2, 4.

In operation, the valve E is moved so that the channel E' registers with the opening left in the port C by the transverse rib C', and with the port B' in the wall of the cylinder B. The piston E is subsequently moved upward until this channel E' is blanked by the rib C' and later, by the cylinder wall itself. The lower channel E² is, meantime, moved up to register with the opening left in the port C by the rib C' and with the inlet A' in the wall of the cylinder A. This last position represents the extreme travel of the piston E so that subsequent movement thereof is downward to reverse the operations described by drawing the channel E² below the port C and subsequently bringing the port E' in position for the inflow of gases to the cylinder B, as described. As has been noted, the phase relation of the valve E to the cycle

of operations going on in the cylinders 1, 3 and all other cylinders that might form part of the motor, can be regulated in accordance with good practice. While the operations of the valve E are going on, the valve D is being moved simultaneously to regulate the exhaust of gases from, first, the cylinder A and, second, the cylinder B. The operations going on in the various cylinders as will be understood.

The description thus far has served to bring out separately the characteristics of the various illustrated embodiments of the improved motor and controlling valves, although some attributes in common may have been touched on. However, certain features common to both, can conveniently be grouped in a single paragraph. In the first place, the ports a', b', etc., in the cylinder walls for the admission and exhaust of gases are disposed adjacent the heads of the cylinders so that the gases are taken directly from the combustion space and are exhausted therefrom by a scavenging action of the working piston which continues throughout the full stroke. All other advantages incident to an "over-head" valve are realized by this disposition of the ports. The integral disposition of these ports adjacent the top of the cylinder head permits the head of the piston e to be of spherical shape and the head of the piston r to be of spherical shape but reversely disposed with respect to the piston rod, so that the combustion space is formed with walls which approximate a true cylinder. Such walls are most advantageous at this part of the motor for the reason that the space of maximum volume and minimum radiating surface is obtained. The heat there is may be easily dissipated by the offset jacketing of the improved cylinder. Another advantageous feature of the improved structure resides in the construction of the controlling valve with respect to the cylinder and the combustion space. It has already been pointed out that the valve permits the inflow of the gases at the upper end of the working cylinder, but it is important to emphasize in this connection that the direct exposure of the valve to the firing space is not disadvantageous in the present construction, because what pressure there is from the gases is exerted internally against the curved surface of the unseated valve. This exposed valve surface is also relatively small so that the net pressure thereon is unappreciable and the heat taken up by the valve from the hot gases is very slight. Whatever heat there is may readily be distributed by conduction throughout the valve body and be drawn off to a great extent by the cooling water in the jacket. By reason of the sheltered position of the valve with respect to the

cylinder and the positive actuation thereof in the absence of springs, the problem of lubrication becomes an easy one.

While no details of the oiling system are illustrated, it will be clear that the oil can be introduced into the piston cylinders very readily, and, in the case of the dual piston valve, the oil may be fed from the outer piston e' to the inner piston r. In all embodiments of the invention, the valve is driven positively and is incased with all of its operating elements so that the danger of injury through the entry of foreign particles, or otherwise, is entirely eliminated. The positive drive does away with all of the objectionable features incident to the use of springs so that the general annoyance of springs is not only removed but absolute reliability is secured. By providing a common inlet port c, C, for proximate cylinders, the mixture admitted to both is bound to be of the same uniform character, and changes in the composition of the mixture due to its short passage to one cylinder and its relatively long passage to another cylinder, as in present day practice, is overcome. The valves themselves are of such a nature as to permit a maximum port area to be employed and also insure the quick opening and closing of these ports. In fact there is no restriction to be placed upon the area of the ports, except considerations of manufacture and efficiency of operation. The cooperating pistons in the dual slide valve serve to open and close the ports very quickly. The last two characteristics mentioned will especially commend the improved motor for use under high speed conditions. The simplicity of construction and operation obtained through the elimination of a great number of parts in the valve gear will be evident to those skilled in the art as known types of motors usually depend upon a control in which there is a separate inlet valve and exhaust valve with their associated parts, for each cylinder. The adaptation of the cylinders themselves and their jackets to the employment of the improved valve also involves an appreciable reduction in the initial cost of manufacture in that a single integral casting has embodied therein the valve chambers, ports, and jacketing for the cylinders and chambers. It will also be evident that the disposition of the valves in the chambers at one side of the working cylinders results in their operation with minimum friction and at an expenditure of very little power in the actuation of the small crank shafts on which the eccentrics are carried.

As was suggested in the preamble, and as will be evident, many modifications in the details of construction and many rearrangements of the parts will suggest themselves to those skilled in the art, but all such modifi-

cations and rearrangements are to be deemed within the spirit of this invention provided they fall within the scope of the appended claims.

5 I claim as my invention:

1. In an internal combustion engine in combination with two of the cylinders therefor, inlet and exhaust ports in each cylinder formed one above the other, two valve chambers cast integral with the cylinder walls, a common inlet port for the two cylinders, and an independent common exhaust port therefor, both communicating with the valve chambers, a tubular piston in each chamber having ports in its circumference to register respectively with the ports of one cylinder and the common ports, and a solid piston disposed within the tubular piston and having channels therethrough to register respectively with the ports in the tubular piston.
- 10 2. In an internal combustion motor in combination with two of the cylinders therefor, valve chambers formed in the cylinder walls and integral therewith, separate inlet and exhaust ports formed for the cylinders, a common inlet port with which the two inlet ports communicate, a common exhaust port with which the two exhaust ports communicate, a sliding valve disposed in each valve chamber to control the passage of gas between one of the cylinders and the common port, said valve comprising two telescoping pistons in the walls of each of which
- 15 30 35 are formed ports adapted to register with each other respectively and with the above mentioned ports, and devices connected oper-

atively to each of the telescoping pistons and to the crank shaft of the motor for driving the said pistons in proper phase relation to each other and to the cycle of operations in all of the cylinders of the motor.

3. In an internal combustion motor in combination with two of the cylinders therefor, two valve chambers cast integral with the cylinder walls, two independent inlet and exhaust ports formed in the wall of each of the cylinders adjacent the combustion space thereof and communicating with one of the valve chambers, a common inlet port communicating with the valve chambers, a common exhaust port communicating with the valve chambers, a sliding valve reciprocably mounted in each valve chamber to control the passage of gas between the common ports and the two cylinders respectively, said sliding valves comprising a sleeve and a piston reciprocably mounted in the sleeve, said piston in each case being formed with channels therethrough and the sleeve in each case being formed with ports to register with the said channels and with the inlet and the exhaust ports respectively, and an eccentric shaft with which the sleeves and the sliding pistons are connected operatively, all of said devices being disposed wholly within the integral walls of the cylinders and valve chambers.

This specification signed and witnessed this 25th day of February, A. D. 1915.

WILLIAM M. LORENZ.
